DESIGN FOR A BIRD CAGE

Abraham Zaha and James Monicatti,
Detroit, Mich.

Application April 14, 1945, Serial No. 119,000

Term of patent 7 years

(Cl. D31—4)

To all whom it may concern:

Be it known that we, Abraham Zaha and James Monicatti, citizens of the United States, residing at Detroit, in the county of Wayne and State of Michigan, have invented a new, original, and ornamental Design for Bird Cages, of which the following is a specification, reference being had to the accompanying drawings, forming part thereof, wherein:

Fig. 1 is a top plan view of a bird cage showing my new design.

Fig. 2 is a view of the cage in side elevation.

Fig. 3 is an end view of the cage.

We claim:

The ornamental design for a bird cage, as shown.

ABRAHAM ZAHA.
JAMES MONICATTI.
